SEWING MACHINE AND PROCESS

Henry J. Ernst, Southgate, Ky.

Application August 18, 1936, Serial No. 96,656

22 Claims. (Cl. 112—130)

My invention relates to a process and device for sewing tape on shoe soles, and particularly the insole of shoes, so that the uppers may be sewn or otherwise fastened to the said tape in the process of shoe manufacture; and this application is a continuation in part of my co-pending application, Serial No. 700,726, filed Dec. 2, 1933, and entitled Sewing machines.

In the employment of my process and machine 10 the tape is fed to the work piece from beneath in a positive way, and the sewing proceeds as usual, the needle passing first through the work and then through the tape. It is an object of my invention to provide a positive but adjustable 15 guide mechanism for the sewing. It is an object of my invention to provide means whereby the sewing can be done with or without tape at will, so that without change in the operation of the sewing machine, the feeding and sewing of the 20 tape can be started at the point desired by the operator, and can be stopped at the point desired by the operator irrespective of a continuation of the sewing itself.

In furtherance of this general object, it is my 25 object to provide a novel means for severing the tape in proper relationship to the sewing operation and for disconnecting the tape fed, while at the same time retaining the severed end of the tape in position for feeding. It is my object to 30 provide means whereby at will, and during the sewing, the feeding of tape may be started. Thus the line of stitching may be caused to project beyond the tape at both ends whereby the ends of the tape are firmly caught.

35 In carrying out the process of treating soles in accordance with my teachings, the operator commences sewing generally at or near an edge of the sole, and at the proper place causes the tape to be fed and caught in the line of stitching, continues sewing the tape adjacent an edge of the sole for the required distance, then discontinues the feeding of the tape and severs it while the stitching continues, continues sewing while turning the sole so as to come back on the other 45 side, at the proper point resumes the feeding of the tape and at the proper point discontinues it while still forming a line of stitches.

It is an object of my invention to provide adequate positive and convenient mechanism for the 50 purposes described; and the various objects of my invention which have not been referred to hereinabove will be clear to one skilled in the art upon reading these specifications.

I accomplish my invention by that construction and arrangement of parts and by that series

of process steps of which I shall now describe certain exemplary embodiments.

Reference is made to the drawings wherein:

Fig. 1 is a perspective view of a sewing machine with parts in section. 5

Fig. 2 is a plan view of a portion of the machine bed, looking down along the lines 2—2 of Fig. 1.

Fig. 3 is a plan view of the bed with parts in section, the section lines being the lines 3—3 of 10 Fig. 1.

Fig. 4 is a sectional view across the machine bed and taken along the lines 4—4 of Fig. 3.

Fig. 5 is an enlarged fragmentary view of the 15 tape slot and the severing mechanism.

Fig. 6 is a view of a portion of the operating mechanism whereby the tape is severed and the feed interrupted.

Fig. 7 is a view of another portion of the same mechanism designed for co-action with the parts 20 shown in Fig. 6.

Figs. 8 and 9 are views showing different stages in the operation of the severing and disconnecting mechanism.

Fig. 10 is a vertical sectional view through the 25 feed mechanism and the control means for the severing mechanism and may be considered as taken along the lines 10—10 in Fig. 11.

Fig. 11 is a view showing the mechanism underneath the machine bed in plan. 30

Fig. 12 is a sectional view showing a portion of the feed mechanism and taken along the lines 12—12 of Fig. 11.

Fig. 13 is a vertical sectional view taken through the rear end of the machine head and 35 showing an alternative feeding arrangement.

Fig. 14 is a sectional view showing the same arrangement as Fig. 13, the section being at right angles and taken along the lines 14—14 of that figure. 40

Fig. 15 shows in plan, an exemplary insole treated in accordance with my process and by my mechanism.

In Fig. 1, I have shown a sewing machine having the usual head 1 and table 5. The main 45 shaft in the head is designated at 6, and arranged to be driven by a belt or by a motor, as may be desired. No special description either of the needle mechanism or of the shuttle mechanism is required since in these respects, the machine 50 is well known in the art. Because of additional mechanism in the base however, such as mechanism to feed and sever the tape, more operating parts are required, and more means for transmitting power from the main shaft 6. Thus I 55

have shown in Fig. 1 in the head 1, three different eccentric 7, 8 and 9, the purpose of which will be clear hereinafter. The machine has feeding mechanism for a work piece 15, which is to be sewn and the formation of the line of stitches by the machine proceeds as is usual in the art. However, beneath the table 5, there is means for feeding tape 16 from a supply not shown. The tape is fed into position to be caught by the line 10 of stitches formed by the machine.

As I have hereinabove indicated, a primary use for my machine is in the manufacture of shoes where it is desired to sew tape upon an insole as shown in Fig. 15, and hereinafter more particularly described. So as to position the tape properly a guiding mechanism having a guiding foot 17 is provided, and this guide mechanism is adapted to be changed as to position by the operator by means of a convenient knee or foot 20 treadle. The operating linkage for the gauge mechanism is shown in Fig. 1, generally at 18. An operating lever is shown at 19. When this lever is thrown by the operator, it operates a mechanism which when actuated by the main feed of 25 the sewing machine, cuts the tape and stops the feeding of the tape without in any other way affecting the operation of the sewing machine. Thus when the operator has been sewing tape, she may stop the tape at any point while continuing 30 to sew from there on. When she desires again to sew tape, she presses downwardly on the operating member 19, and the feeding and the sewing of the tape are resumed. Means are provided for releasing the tape from the tape guide as 35 when it is desired to change the tape. The various mechanisms and the problems connected therewith will be taken up in order by reference to certain of the figures.

The guide

By reference to Figs. 2 and 3, it will be seen that the guide mechanism comprises a bar 20 on one end of which is the guide foot 17. The bar is pivoted in a channel 21, and the bar may be 45 rocked in this channel by pressing down on the operating handle 22, whereby to raise the foot 17. Constructions of this character are common and need not be particularly described.

The channel 21 however, is fastened to a rack 50 bar 23, mounted below the bed plate 5 in a suitable channel. The rack bar has teeth meshing with the teeth of the segmental gear 24, mounted upon a shaft 25 in the frame of the machine. On this shaft, as indicated in Fig. 1, there is a lever 55 26 having a spring return 27. The lever is actuated by the linkage mechanism 18, which will be understood as connected to a suitable foot or knee treadle. By this means the operator can gauge and vary the distance of the tape from the 60 edge of the work.

The tape guide

By reference particularly to Figs. 4 and 5, it 65 will be seen that below the bed plate 5 there is a suitable slot 26, through which the tape 16 passes. A rotary dog 27 feeds the tape. The slot is so shaped as at 26a, as to lead the tape upwardly through the bed and into position for sewing against the work piece 15.

Tape severing means

As shown in Fig. 3, there is a second rack bar 28, mounted in a suitable slide below the machine bed. This rack bar meshes with a segmental gear 29. To the bar there is attached an

operating means 30, and to this in turn a knife 31. The end of this knife is most clearly shown in Fig. 5, as comprising a blade 31a and a rounded member 31b, underlying the tape 16. The edge of the knife blade 31a is in sliding contact with the top of the member 26a. In a slot overlying the tape slot, a member 32 is mounted slidably and is urged to the left in Fig. 5 by means of a spring 33. The operating member 30 has its end shaped to provide a slanting shoulder 30a, and to the 10 member 32 there is attached a cam member 34 having a slanting shoulder 35. When the operating member 30 moves to the left in Fig. 5, the cam member 34 rides down the shoulder 30a so as to permit the sliding member 32 to press the 15 tape tightly against the end of the member 26. This keeps the tape from twisting and assures the formation of a smooth cut. The knife blade 31a of course, rides over the top of the member 32.

Tape feeding and release mechanism

20

As I have hereinabove indicated, the tape is fed by means of a rotary dog 27, shown in Fig. 4. The tape is held against this dog so as to be fed by means of a lever 36 pivoted as at 37' in the slot 26, and having a projecting operating end 37, this end, as shown in Fig. 3, being T shaped so as to be engaged by an operating bar 38. The bar as shown at 38a in Fig. 1, is hollowed out below the member 37 so as not to interfere 30 with the passage of the tape 16. The bar 38 is pivoted as at 39, and may be held elsewhere by screws 40, passing through slots in the bar. It will be evident that if the left-hand end of the bar 38 is lowered, it will release the end of the lever 36, so that this lever no longer presses the tape against the rotary feed dog 27. In this way, the tape may be released from the rotary feed dog so as to be withdrawn from the slot 26.

The right-hand end of the bar 38 is carried 40 upwardly and over as shown at 41 in Fig. 4. A spring 42 surrounding a rod 43 bears against a nut 44 and presses the end 41 of the bar 38 downwardly, so as to cause the lever 36 to maintain the tape in contact with the rotary feed dog. A 45 lever operating mechanism 45 in Fig. 1 is pivoted to the bar 38 at 46, and as shown most clearly in Fig. 4, bears an eccentric roller 47, non-rotatably mounted with respect to the lever 45. As the lever 45 is thrown over this roller engages 50 against the machine bed 5 and raises the right-hand end of the bar 38, so as to release the feed as described.

As will be clear by reference to Fig. 10, the 55 rotary feed dog 27 is mounted on a shaft 93 journaled in a machine frame. This shaft bears a gear 92, meshing with another gear 90, splined on a shaft 51. By reference to Figs. 11 and 12, it will be seen that this shaft 51 bears a ratchet 52. A pawl housing 53 having a pawl 54, pivotally mounted therein, and actuated by a spring 55 is rotatably mounted on the shaft 51. It bears a slotted extension 56 to which a stud may be mounted as by means of a bolt 57. This stud rides in a channel 58, which is part of an operating arm 59 fixed on a shaft 60, all as is shown in Fig. 12. It will be clearly understood that as the shaft 60 rocks in the direction of the arrows in Fig. 12, the pawl housing 53 will likewise rock. The engagement of the pawl with the ratchet 52 70 will provide for rotation of the shaft 51, always in the same direction.

To prevent a tendency of the shaft 51 to turn back with the pawl, I provide frictional means 75 constituting a spring 61 shown in Fig. 11, bearing 75

against a washer 62, held as by means of bolts 63 to the end of the shaft 51, and at its other end bearing against a washer 64 on a bearing member 65 of the machine frame.

5 The shaft 60 is thus the means whereby a tape feeding motion is transmitted from the main shaft 6 of the machine to the rotary feed dog ultimately. In Fig. 11, the shaft 60 is shown as having an arm 66, to which the arm 67 of the eccentric 7 is pivoted.

10 For a better understanding of the machine mechanism it may be pointed out in connection with Fig. 11, that beside the shaft 60, there are two other shafts in the base of the machine. The shaft 68 is the shuttle shaft, and is connected to a shuttle mechanism 69 of known type. This shaft bears an arm 69, which is connected by means of a pin 70 to a rocker arm 71. This arm in turn is pivoted to the arm 72 of the eccentric 9 as is usual in a sewing machine. The operation 15 of the eccentric 9 is to give to the shuttle shaft 68 a rocking motion. The third shaft is shown at 73. An arm 74 on this shaft is pivoted as at 75 to the arm 76 of the eccentric 8, whereby the shaft 73 is given a reciprocating motion.

20 The shafts 60 and 73 combine to produce the reciprocating and up and down motion of the main feed dog of the sewing machine. The main feed dog is indicated at 77 as fastened to an operating arm 78. The left end of this arm is pivoted as at 79 to a crank 80 on the shaft 60. The other end of the bar 78 is bifurcated as at 78a to engage a pin 81, mounted upon an arm 82 fixed on the shaft 73. The combined rocking motions of the shafts 60 and 73 give to the feed dog 77, the requisite back and forth and up and down motions as well known in sewing machines. There will, of course, be a suitable presser foot such as the rotary presser foot 83, or some equivalent.

Control mechanism

25 Control of the tape feeding mechanism is had through a member shown at 19 in Figures 1, 2 and 3. By reference to Fig. 6, it will be seen that the operating handle 19 is affixed to a shaft 84, and that this in turn is keyed or pinned to a release bar 85. Surrounding the shaft 84 there is a sleeve 86, to the upper end of which a segmental pinion 29 is attached. To the lower end an angular crank 87 is keyed. From the angle of this crank a pin 88 projects downwardly.

30 In Fig. 10 these elements are shown in assembled relationship. The sleeve 86 is journaled in the bed 5 of the sewing machine. The pinion 29 lies in a recess in the bed; and by reference to Fig. 3 it can be seen how this pinion meshes with the rack 28, which actuates the severing knife 31.

35 Referring now to Fig. 8, it will be seen that a striker bar 89 is pivoted upon the pin 88. The upper end of the angle member 87 lies against the hub of a gear 90, splined but slideable upon the feed shaft 51. A spring 91 urges this gear to the right in the several figures. The gear 90 meshes with a gear 92 on the shaft 93 which bears 40 the rotary feed device 27. With the gears in the position shown in Fig. 8, the shaft 93 is connected to the shaft 51 so that the latter shaft can drive the rotary feed dog 27. If the gear 90 is pushed to the left against the tension of the spring 91, to the left against the tension of the spring 91, as shown in Fig. 9, the driving connection will be 45 broken.

50 The mere operation of rotating the control handle 19 however, does not effect disengagement of the gears 90 and 92. What happens is that the release bar 85 throws the knock-out bar 89

5 to the position shown in Fig. 8, where the end of this knock-out bar lies in the path of a cam member 94 on the shuttle shaft 68 of the machine. When this shaft rotates to the position shown in Fig. 9, the knock-out bar 89 is pushed 10 upwardly thereby rocking the angular lever 87, and causing the end of it to move the gear 90 to disengaged position. Thus the disengagement of the feed is accomplished in timed relationship to the stitching. The angular lever 87, as has 15 been said, is keyed to the sleeve 86. Therefore, when the angular lever moves to the position shown in Fig. 9, it moves the sleeve and in turn the pinion segment 29 attached thereto. In this way the knife is also actuated in timed sequence 20 to the sewing operation. The knock-out bar 89 is urged to normal position by a spring 95, shown in Figs. 9 and 11. The normal position of the knock-out bar is shown in the latter figure. A spring 96, one end of which is attached to a 25 link 97, mounted on a pin 88, and the other end of which is attached to the frame of the sewing machine as at 98, serves to urge the angular lever 87 into the normal position shown in Figs. 8 and 11.

30 In order to prevent the recurrence of a cut each time the shuttle shaft 68 oscillates, and in order to keep the rotary feed dog 27 disconnected, I provide a latching mechanism comprising a pivoted latch 99 urged upwardly by a spring 100. The end of the pin 88 is beveled as shown at 101, so that it can depress and ride over the latch member 99. When the angular lever 87 is in the position shown in Fig. 9, the latch 99 engages behind the pin 88 and holds the lever in 35 that position.

35 It will be noted in Fig. 10, that the shaft 84 is considerably longer than the sleeve 86, and that the shaft and the operating handle 19 are urged upwardly by a compression spring 102. The latch 99 lies beneath the end of the shaft 84, so that if the operating lever 19 is depressed from above, it will serve to depress the latch 99, thereby releasing the pin 88 and permitting the angular lever 87 to return to the position shown in Figs. 40 45 8 and 11.

45 In the operation of this part of my device, if tape is being sewn and the operator desires to discontinue the sewing of the tape, she moves the operating handle 19 to the left. This, 50 through the operation of the bar 85, causes the throw-out bar 89 to assume the position shown in Fig. 8. When the shaft 68 oscillates, the cam 94 strikes the throw-out bar and brings the angular lever 87 to the position shown in Fig. 9. This 55 does two things:—first the end of the angular lever carries the gear 90 to the left, thereby disengaging it from the gear 92, and discontinuing the rotation of the feed dog 27. Second, it rotates the sleeve 86, and with it the segmental 60 pinion 29, which moves the rack 28 to the left, effecting a severing cut on the tape by means of the knife blade 31 also in timed sequence to the sewing operation.

65 When this happens the pin 88 engages behind the latch member 99. Thus the gear 90 is maintained out of engagement with the gear 92 and the knife 31 is prevented from making additional cuts. The sewing, however, can continue in an uninterrupted way. Of course, as soon as the 70 cam 94, which has depressed the knock-out bar 89, releases that bar, the bar swings to the left under the influence of the spring 95, out of the way of the cam. Sewing is then continued without tape feeding for as long as may be desired. 75

When the operator desires to resume the feeding and sewing of tape, she strikes downwardly upon the operating handle 19. The effect of this is to release the latch 99 permitting the angular lever 87 to swing back under the influence of spring 96, to the position shown in Figs. 8 and 11. The gear 98 thereupon engages with the gear 92 and the feeding of tape is resumed.

In Figs. 13 and 14, I have shown alternative operating mechanism. Here the shaft 6 is provided with the same eccentric 9 as before, for operating the shuttle shaft 68, and with the eccentric 8 for operating the shaft 60. In place however, of the eccentric 1 for operating the shaft 73, I have shown a pair of elliptical gears 103 and 104. The first of these is fastened upon the shaft 6. The second is mounted upon a supplementary shaft 105, mounted in the machine frame. The gear 104 bears a pin or crank member 106, from which a link 107 passes to the lever 74. A more marked variation of motion can be obtained in this way. The shaft 51 which turns the rotary feed dog 27 through mechanism heretofore described, may in this instance be rotated continuously. A worm 108 may be fastened either on the shaft 105 or on the shaft 6. Where it is fastened upon the shaft 105, as shown, the worm will have uneven motion imparted to it through the action of the elliptical gears. A worm gear 109 engages the worm 108, and is fastened upon a shaft 110 suitably journaled in the machine frame and bearing on its lower end a bevel gear 111. This in turn meshes with a bevel gear 112 on the shaft 51. I prefer in this instance to make a frictional connection between the gear 112 and the shaft. To this end I pin an abutment member 113 to the shaft and place between it and the gear 112, a compression spring 114. This permits continued rotation of the gears if for any reason the rotation of the shaft 51 should be stopped.

It is to be understood that this modification provides a different means for imparting motion to the shaft 51. The shaft, incidentally in this modification, is continued all the way out to the right hand end of the machine as shown in Figure 13. While in the first described embodiment the shaft 51 was given an intermittent movement, in this modification it is given a continuous but pulsating movement. It will be understood that the mechanism described immediately above takes the place of the assembly, including the lock nuts 63, washers 62 and 64, and spring 61, as well as the mechanisms comprising the ratchet 52, the pawl housing 53 together with the arm 56, the pawl 54, spring 55, stud 57, and the arm 59.

In Fig. 15, I have shown an insole 115 treated in accordance with the process of my invention. In making this insole the operator began to sew at the point marked A. At the point marked B, she depressed the operating handle 19 and began to feed the tape 16, which was caught by the line of stitching 116. By means of the guide member 17, she positioned her tape upon the insole as desired. At the point C, she threw the operating handle 19 to the left, thereby severing the tape and discontinuing the feeding thereof, although the line of stitching continued to the point D, where she turned the sole and continued sewing in the same manner adjacent the opposite edge thereof. At the point E, she began feeding the tape again, and at the point F, discontinued it.

The face of the insole shown in Fig. 15, was 75 the lower face during the sewing operation. The

tape was fed from beneath. The operator did not see the tape as it was being sewn, but could control its position and its starting and ending points as aforesaid. The sewing operation on this sole was continuous and the operation of the 5 machine was not interrupted from the time the sewing operation began until the operation ended. It will be seen at both ends of the sole the line of stitching continues beyond the ends of the tape; and the ends of the tape are securely caught 10 in the line of stitching.

Modifications may be made in my invention without departing from the spirit thereof.

Having thus described my invention what I claim as new and desire to secure by Letters Patent, is:

1. In a sewing machine for sewing tape or the like, to a work piece, a fixed tape guide, feeding means for moving tape in said guide, means for severing said tape and means for actuating 20 said severing means in timed sequence to the sewing operations of said machine.

2. In a sewing machine having the usual sewing mechanism, including an operating shaft beneath the bed of said machine, a fixed tape guide, 25 feeding means for tape and severing means for tape, operating means for said severing means, manual control means for said operating means and means for transmitting power to said operating means from said shaft in timed sequence 30 to the movements thereof.

3. In a machine for sewing tape to a work piece, fixed guiding means for tape, feeding means for tape and severing means for tape, means for actuating said severing means and for concurrently de-energizing said feeding means, and means for causing actuation of said last-mentioned means in timed sequence to the sewing operations of said machine. 35

4. In a sewing machine, sewing mechanism, 40 tape guiding means, tape feeding means and tape severing means, a common means for operating said severing means and for de-energizing said feeding means, means for actuating said operating means in timed sequence to the sewing operations of said machine and releasable means for retaining said last-mentioned means in actuated position.

5. In a sewing machine, a fixed tape guide, severing means for tape passing through said 50 guide, means for actuating said severing means in timed sequence to the sewing operations of said machine and releasable means for maintaining said severing means in inactive position after actuation thereof. 55

6. In a sewing machine for sewing tape onto a work piece, a bed, a fixed tape guide in said bed, means for feeding tape in said tape guide, severing means for said tape and means for actuating said severing means in timed sequence to the sewing operations of said machine whereby said tape may be severed during the continuance of a sewing operation and the severed end of said tape caught and held to said work piece 60 by thread forming a part of a line of stitching made by said machine, passing over the severed end of said tape.

7. In a sewing machine having a bed, a tape guide in said bed, a rotary feed dog for said 70 tape and releasable driving means for said rotary feed dog, severing means for said tape, concurrently operating means for said severing means and said driving means and means for actuating said operating means in timed sequence to the 75

- sewing operations of said machine for the purpose described.
8. In a sewing machine having a bed, a tape guide in said bed, a rotary feed dog for said tape and releasable driving means for said rotary feed dog, severing means for said tape, concurrently operating means for said severing means and said driving means and means for actuating said operating means in timed sequence to the sewing operations of said machine for the purpose described, and latching means for said actuating means.
9. In a sewing machine having a bed, a tape guide in said bed, feeding means for tape moving in said guide, a releasable driving mechanism for said feeding means, a severing means for said tape, common operating means for said last two mentioned means, and manual control means, said operating means having actuating means adapted to be brought into a position for actuation by a moving part of said sewing machine, said manually operated means adapted to bring said actuating means into position for said actuation.
10. In a sewing machine having a bed, a tape guide in said bed, feeding means for tape moving in said guide, a releasable driving mechanism for said feeding means, a severing means for said tape, common operating means for said last two mentioned means, and manual control means, said operating means having actuating means adapted to be brought into a position for actuation by a moving part of said sewing machine, said manually operated means adapted to bring said actuating means into position for said actuation and means for latching said operating means in actuated position.
11. In a sewing machine of the character described, a bed, a tape guide in said bed, tape feeding means in said guide, releasable driving means for said feeding means, a tape severing means and a common operating means for said tape severing means and said driving means, actuating means for said operating means comprising a member adapted to be moved into a position of engagement with a moving part of said sewing machine, latch means for holding said operating means in actuated condition and manual control means, one movement of which serves to bring said actuating means into actuating position and another movement of which serves to release said latch means.
12. In a sewing machine for the purpose described, a bed, a feed shaft and an operating shaft, a tape guide in said bed, a rotary feed dog in said tape guide, a releasable driving connection between said dog and said feed shaft, a slideable tape severing means, a shaft, means on said shaft for sliding said tape severing means, means on said shaft for disconnecting said driving connection, a cam on said operating shaft, a movable member adapted to be struck by said cam to operate said severing and driving means, and means for bringing said last-mentioned member into a position for actuation by said cam.
13. A sewing machine for the purpose described and having tape severing, feeding and guiding means, a control means comprising a hollow shaft journaled in said bed, pinion means on said shaft engaging said severing means, lever means on said shaft for disconnecting said feeding means, a pivoted striker bar on said lever means for actuation by a cam on a moving element of said sewing machine, a shaft passing through said hollow shaft and bearing moving means for said striker bar.
14. A sewing machine for the purpose described and having tape severing, feeding and guiding means, a control means comprising a hollow shaft journaled in said bed, pinion means on said shaft engaging said severing means, lever means on said shaft for disconnecting said feeding means, a pivoted striker bar on said lever means for actuation by a cam on a moving element of said sewing machine, a shaft passing through said hollow shaft and bearing moving means for said striker bar.
15. In a sewing machine, a main drive shaft and a pair of shafts cooperating to actuate a main machine feed, an eccentric mounted on said main shaft and an operative connection between said eccentric and one of said last-mentioned shafts, an elliptical gear on said main shaft, a second elliptical gear on a supplementary shaft and an operative connection between said second elliptical gear and the second of said feed operating shafts.
16. In a sewing machine of the character described, tape guiding means and rotary tape feeding means, a connection between said feeding means and a feed shaft, a main shaft, an elliptical gear on said main shaft, a second elliptical gear on a supplementary shaft and meshing with said first gear and a continuous driving connection between said supplementary shaft and said feed shaft.
17. A process of sewing tape to a work piece which comprises commencing a line of stitching in said work piece and, intermediate the said line of stitching, feeding a tape thereto, so that the end of said tape is caught in said line of stitching, continuing to sew said tape to the extent desired, then severing said tape in timed sequence to the formation of stitches in said line of stitching so that the severed end of said tape is caught in said line of stitching, and continuing the formation of said line of stitching, all of said operations being carried on without interruption of the sewing operation, and locating the position of said tape on said article by means of a movable guide for said article, and by moving said guide during said sewing operation.
18. A process of sewing tape to a work piece such as the insole of a shoe, which comprises commencing the formation of a line of stitching by means of a sewing machine in said work piece and during continuance thereof feeding a tape from beneath to said work piece so as to cause said tape to be caught in said line of stitching and afterwards severing said tape in timed sequence to said line of stitching and continuing the formation of said line of stitching, all as a sequence of operations during the uninterrupted sewing of said work piece and locating the position of said tape on said article by means of a movable guide for said article and by moving said guide during said sewing operation.
19. A process of treating insoles for lasting, which comprises forming a line of stitching in an insole having a relationship to the edge thereof and during the formation of said line of stitching feeding a tape thereto from beneath said insole, so that the needle used in the sewing passes first through said insole and then through said tape, so that the end of said tape is caught in said line of stitching, continuing to sew said tape while

- proceeding with said stitching along one side of said insole, severing said tape in timed sequence to the formation of stitches in said line of stitching so that the severed end of said tape is caught in said line of stitching, and continuing the formation of said line of stitching to a point adjacent an end of said insole, thereupon, while continuing the operation of sewing, turning the insole so that the line of stitching proceeds in relation to the other side of said insole, and repeating the operations hereinabove set forth, finishing said insole with a line of stitching extending beyond the end of the tape.
20. In a sewing machine, means forming a tape feeding guide, a rotary feed dog having a portion effective upon tape in said guide, a pivoted lever having a portion located to press tape in said guide against said dog, and means for operating said lever, said means comprising resilient means for holding said lever in tape feeding position and manually operable means operating against the force of said resilient means to permit said

lever to move to non-feeding position, whereby tape may be withdrawn from said guide.

21. In combination in a sewing machine, means forming a tape feeding guide, a tape severing knife moving substantially transverse to said guide, and a means operable in response to movement of said knife to press said tape flatwise against a face of said guide, whereby to hold said tape during the cutting operation. 5

22. In combination in a sewing machine, means forming a tape feeding guide having an upwardly directed end portion, a knife horizontally slidable across said end portion, a tape holding means horizontally slidable in a different direction to press said tape against the upwardly directed 15 portion of said guide means during a cutting operation, means for urging said last mentioned member into tape holding position and means on said knife, effective upon movement thereof, to control the position of said tape holding means. 20
